LOCOMOTIVE STOKER

William L. Lentz, Tuckahoe, N. Y., and Eugene Martin, Erie, Pa., assignors to The Standard Stoker Company, Incorporated, a corporation of Delaware

Application November 17, 1938, Serial No. 240,944

8 Claims. (Cl. 105—234)

This invention relates to a locomotive tender having installed therein the tender unit of a stoker.

An object of the invention is to provide a novel tender and stoker construction wherein the stoker tender unit is conveniently and economically installed in existing as well as new tenders.

Another object of the invention is to so construct the tender and stoker unit, that when assembled, the stoker unit will displace as little of the water and coal carrying space of the tender as possible.

Still another object of the invention is to provide a construction of the type described that is rigid and durable and wherein the stoker drive mechanism is readily accessible without disturbing or dismantling the stoker or tender.

Still another object of the invention is to provide a novel tender unit of a stoker that is simple in construction, easily assembled, inexpensive to manufacture and in which parts most likely to require replacement or repair are conveniently removable and readily accessible.

Other objects, advantages and novel details of construction will be apparent during the course of the following description and appended claims taken in connection with the accompanying drawings, in which

Fig. 1 is a central longitudinal vertical section of adjacent portions of a locomotive and tender with the stoking mechanism applied thereto and shown in similar section;

Fig. 2 is a sectional view taken on the line 2—2 of Fig. 1;

Fig. 3 is a sectional view taken on the irregular line 3—3 of Fig. 1;

Fig. 4 is a sectional view taken on the line 4—4 of Fig. 1;

Fig. 5 is a sectional view taken on the irregular line 5—5 of Fig. 3;

Fig. 6 is a sectional view taken on the line 6—6 of Fig. 1;

Fig. 7 is a sectional view taken on the line 7—7 of Fig. 6;

Fig. 8 is a sectional view taken on the line 8—8 of Fig. 6;

Fig. 9 is a sectional view taken on the line 9—9 of Fig. 4;

Fig. 10 is an enlarged fragmentary view of a portion of Fig. 1 showing the novel tender and stoker construction;

Fig. 11 is a fragmentary isometric view through the tender and stoker trough just forward of the rear slope sheet of the tender fuel bin and looking toward the rear of the tender; and

Fig. 12 is a fragmentary sectional plan view at the forward end of the tender taken through the bulkhead.

In the drawings, a locomotive is indicated generally by the letter L, a tender is indicated generally by the letter T and a stoker, shown applied to the locomotive and tender, is designated by the letter S.

The locomotive L is provided with a firebox 10 having a backwall 11, the latter having a firing opening 12 for manual or stoker firing. The tender T has a frame 13 supporting the fuel compartment 14 and water compartment 15. The stoker S includes a riser conduit 16 communicating with the firing opening 12 and delivering fuel onto a distributing plate 17, at the rear of which plate is a jet head 18 from which issue blasts of fluid under pressure for projecting the fuel from the plate 17 into the firebox. The riser conduit 16 is rigidly supported in any suitable manner, as by a bracket 19 which is secured to the backwall 11. A frame 20 surmounts the upper end of the riser conduit 16 and embraces the upper portion of the firing opening 12. The frame 20 is provided with a fire door 21 permitting, when open, manual firing of fuel and access to the firebox. Fuel is elevated through the riser conduit 16 by a screw conveyor 22.

The lower end of the riser conduit 16 is universally connected at 23 to a conduit 24 leading rearwardly toward the tender. A universal and longitudinally extensible connection 25 joins the rearward end of the conduit 24 with the forward end of the tender unit of the stoker. The universal connection 23 and the universal and longitudinally extensible connection 25 provide for relative movement between the rigidly mounted riser conduit 16 and rigidly mounted tender unit of the stoker when the locomotive and tender round curves or pass over switches and turntables.

A screw conveyor 26 housed in the conduit 24 is universally connected with the screw conveyor 22 by a link 27 and advances fuel to the riser conduit 16.

The tender fuel bin is provided with a floor 28 and the extension 29 thereof forward of the bin forms a tender deck. The tender deck 29 and fuel bin floor 28 are provided with a continuous longitudinally elongated centrally disposed cut out or opening 30. An open mouth trough 31, disposed in the water compartment 15, is arranged to receive fuel from the bin 14 through the opening 30 in the floor thereof. The upper marginal sides of the trough 31 are provided with the outwardly extending flanges 32 and 33, respec-

50
55

5 tively, overlapping the fuel bin floor 28 adjacent the marginal sides of the opening 30 therein, whereby the trough 31 is supported by the fuel bin floor. Since the opening 30 in the bin floor continues through the tender deck 29, it will be seen that the trough 31 can be slid rearwardly into place in the water compartment 15 from the forward end of the tender. After the trough 31 is slid into position, the flanges 32 and 33 are welded to the fuel bin floor 28, as at 34 and 35, providing a water tight seal.

10 The front wall 36 of the water compartment 15 is cut out at 37 following the contour of the trough 31, permitting insertion of the latter, after which the front wall 36 and the trough 31 are welded as at 38 providing a water tight seal. The trough 31, which is open at its forward end, is provided at that end with a short forwardly extending tubular casting 39. This tubular casting is provided at its rearward end with an outwardly extending flange 40 conforming with the shape of the trough and fitting within the forward end of the trough. A weld 41 joining the marginal edge of the flange 40 with the inner surface of the trough 31 rigidly secures the tubular casting 39 with the trough 31. The forward end of the tubular casting 39 is connected with the rearward end of the intermediate conduit section 24 by the aforementioned universal and extensible connection 25. A screw conveyor 42 is disposed in the trough 31, the forward end of the screw conveyor extending through the tubular casting 39 where it is universally connected with the rearward end of the screw conveyor 26.

15 A plurality of transversely extending plates 43 are disposed in the water compartment 15 and are secured at their lower ends to the floor 44 thereof in any suitable manner, as by the angles 45, and similarly, at their upper ends to the underside of the fuel bin floor 28 by the angles 46. The plates 43 are recessed, as at 47, to receive the trough 31. These plates serve as water baffles and also as additional supports for the trough by means of the angles 48 which are securely attached to the plates 43 and fit closely against the sides of the trough.

20 In the water compartment 15 there is provided a water tight compartment 49, disposed rearward of the fuel bin floor 28 and beneath the rear slope sheet 50 of the fuel bin. The compartment 49 is formed by the front wall 51, rear wall 52, side walls 53 and 54, and the top and bottom walls are formed by the rear slope sheet 50 and the water compartment floor 44, respectively. The rearward end of the trough 31 extends into the compartment 49 through an opening 55 in the compartment front wall 51. This opening 55 follows the contour of the trough, and the weld 56 joining the outside surface of the trough to the wall 51 forms a water tight seal. The various walls of the compartment 49 are joined together by suitable means, as by the angles 51, the joints being made water tight by suitable means, as by welding.

25 The trough 31, which as stated before extends into the compartment 49, is open at its rearward end. An end plate 58 forms a closure for the open rearward end of the trough 31, and is rigidly secured to the trough by means of an angle 59 extending circumferentially of the trough at the rearward end thereof. A casing 60 housing gearing, through which the screw conveyor 42 is driven, is rigidly secured to the end plate 58 in any suitable manner, as by the bolts 61, and is provided with a removable cover 62.

30 The gear drive mechanism includes a shaft 63 journaled in the bearings 64 and 65 of the gear casing 60 and gear casing cover 62, respectively. The bearing 64 extends through an opening 66 in the trough end plate 58, allowing the shaft 63 to extend into the trough 31 for driving attachment in any suitable manner to the screw conveyor 42. A gear 67 is keyed on the shaft 63 and meshes with a small gear 68 keyed on a shaft 69 which is journaled in the bearings 70 and 71 of the gear casing 60 and gear casing cover 62, respectively. Keyed on the shaft 69 is a large gear 72 meshing with a small gear 73 keyed on a shaft 74 which is journaled in the bearings 75 and 76 of the gear casing 60 and gear casing cover 62, respectively. The shaft 74 is coupled as at 77 to a drive shaft 78 extending longitudinally of the trough 31 to the forward end of the tender, there being connected to a prime mover or any other suitable power means not shown.

35 The drive shaft 78 is enclosed in a water tight sleeve 79 extending through the water compartment 15 from the compartment 49 through the front wall 36 of the tank. A weld 80 forms a water tight connection between the sleeve 79 and the front wall 51 of the compartment 49 and a weld 81 forms a water tight connection between the sleeve 79 and the front wall 36 of the tank. An annular filler piece 82 embraces the portion of the sleeve 79 projecting through the front wall 36 of the tank and fits closely against the front wall 36. The welds 80 and 83 provide a water tight connection between the filler piece 82, the sleeve 79 and tank front wall 36. A bearing 84 for the drive shaft 78 is rigidly secured to the filler piece 82 by the threaded bolts 85 and lock nuts 86.

40 Fuel from the fuel bin 14 enters the trough 31 through the opening 30 in the floor thereof. A plurality of plates 87 normally form a closure for the open mouth of the trough and are arranged to be successively slid forwardly to uncover successive portions of the opening 30. The plates 87 are mounted in guide members 88 and 89 coextensive with the trough and rigidly secured to the upper inner surface of the side walls thereof in any suitable manner as by the welds 90. Openings 91 are provided in the plates 87 for insertion of a hook to draw the plates forwardly or push them rearwardly. A crusher 92 cooperating with the screw conveyor 42 for reducing the large lumps of fuel to a size suitable for firing is rigidly secured to the flange 40 of the tubular casting 39 by any suitable means, as by the bolts 93.

45 The rear slope sheet 50 is provided with an opening 94 through which access may be gained to the compartment 49 for purposes of repair or replacement to the gearing and gear housing 60. A cover 95 normally forms a closure for the opening 94 and is hinged at 96 to the rear slope sheet 50. The lower edge of the cover 95 overlaps the fuel bin floor 28 and is provided with the recesses 97 and 98 affording clearance respectively, for the trough flange 32 and guide 88, and the trough flange 33 and guide 89.

50 Forward of the coal gate 99, which is located between the bulkheads 100 and 101, there is provided a shoveling platform 102 resting on the tender deck 29, the upper surface thereof being level with the upper surface of the trough flanges 32 and 33. The shoveling platform 102 forms a cover over the opening 30 in the tender deck 29 and over that portion of the trough 31 that ex-

tends forwardly of the coal gate 99. The shoveling platform 102 is cut back or recessed, as shown in Fig. 12 at 103 and 104 to fit around the trough flanges 32 and 33. Rigidly secured to the undersides of the shoveling platform 102 and in alignment with the guides 88 and 89 are the guides 105 and 106 in which the foremost of the plates 87 can slide beneath the shoveling platform 102. The rearward end of the shoveling platform 102 is provided with a centrally disposed recess 107 arranged to register with the opening 91 in the rearward portion of the foremost slide plate 87 when it is drawn forwardly beneath the shoveling platform 102. The recess 107 thus provides for access to the slide plate when it is beneath the platform 102, by permitting insertion of a hook therethrough into the opening 91 of the slide plate.

We claim:

1. In a tender, a fuel bin having a floor, a tender deck forward of said fuel bin forming a continuation of said fuel bin floor, said deck and floor having a continuous longitudinally elongated centrally disposed opening extending from the forward end of said deck to the rearward end of said floor, a stoker trough arranged to receive fuel from said bin, said trough having laterally projecting flanges overlapping said floor adjacent the marginal sides of the opening therein, the opening in said deck being of a width such that the said trough flanges will overlap the deck upon insertion and removal of said trough through the forward end of the tender, the overlapped portion of said deck forming a guide support for said trough during its insertion and removal, and a shoveling platform supported on said deck forming a cover for the opening therein, the top surface of said platform being level with the top surface of said trough flanges.

2. In a tender having a fuel compartment and a water compartment, a floor for said fuel compartment, said water compartment extending beneath said floor, a tender deck forward of said fuel bin forming a continuation of said fuel bin floor, said deck and floor having a continuous longitudinally elongated centrally disposed opening extending from the forward end of said deck to the rearward end of said floor, a stoker trough arranged to receive fuel from said bin, said trough having laterally projecting flanges overlapping said floor adjacent the marginal sides of the opening therein, the opening in said deck being of a width such that the said trough flanges will overlap the deck upon insertion and removal of said trough through the forward end of the tender, the overlapped portion of said deck forming a guide support for said trough during its insertion and removal, the outer surface of said trough contacting the water in said water compartment, and a shoveling platform supported on said deck forming a cover for the opening therein, the top surface of said platform being level with the top surface of said trough flanges.

3. In a tender, a fuel bin having a floor and a rear slope sheet, said floor having a longitudinally elongated centrally disposed opening and said rear slope sheet having an opening in its lower portion forming a continuation of the opening in said floor, a stoker trough arranged to receive fuel from said bin, said trough extending rearward of said floor beneath the opening in said rear slope sheet and having laterally projecting flanges overlapping said floor adjacent the marginal sides of the opening therein, and a movable cover for the opening in said rear slope sheet

providing access when open to the rear of said trough.

4. In a tender having a fuel and a water compartment, partition plates separating said fuel compartment from said water compartment including a fuel compartment floor and rear slope sheet, said floor having a longitudinally elongated centrally disposed opening and said rear slope sheet having an opening in its lower portion forming a continuation of the opening in said floor, a stoker trough arranged to receive fuel from said bin, said trough extending rearwardly of said floor beneath the opening in said slope sheet, said trough having laterally projecting flanges overlapping said floor adjacent the marginal sides of the opening therein, the outer surface of said trough contacting the water in said water compartment, means providing a water tight connection between said flanges and said floor, a water tight compartment rearward of said floor and beneath said rear slope sheet enclosing the rearward end of said trough and embracing the opening in said rear slope sheet, and a movable cover for the said last named opening.
5. In a tender having a fuel compartment and a water compartment, partition plates separating said fuel compartment from said water compartment including a fuel compartment floor, said floor having a longitudinally elongated opening, a trough arranged to receive fuel from said bin, the outer surface of said trough contacting the water in said water compartment, a water tight connection between said trough and said fuel bin floor, said trough extending forwardly through the front wall of said water compartment, a water tight connection between said trough and said front wall, a tubular conduit having its rearward end fitting within the lower forward end of said trough, said tubular conduit adjacent its rearward end having an outwardly projecting flange formed therewith, the outer edge of said flange following the contour of the inner surface of said trough and fitting closely therewith, and means rigidly uniting said trough and the flange of said tubular conduit.
6. In a tender, a fuel bin having a floor and a rear slope sheet, said floor having a longitudinally elongated centrally disposed opening and said rear slope sheet having an opening in its lower portion forming a continuation of the opening in said floor, a stoker trough arranged to receive fuel from said bin through the opening in the floor thereof, said trough extending rearward of said floor beneath the opening in said rear slope sheet, and a movable cover for the opening in said rear slope sheet providing access when open to the rear of said trough.
7. In a tender having a fuel and a water compartment, partition plates separating said fuel compartment from said water compartment including a fuel compartment floor and rear slope sheet, said floor having a longitudinally elongated centrally disposed opening and said rear slope sheet having an opening in its lower portion forming a continuation of the opening in said floor, a stoker trough arranged to receive fuel from said bin, said trough extending rearwardly of said floor beneath the opening in said slope sheet, the outer surface of said trough contacting the water in said water compartment, a water tight compartment rearward of said floor and beneath said rear slope sheet enclosing the rearward end of said trough and embracing the

opening in said rear slope sheet, and a movable cover for the said last named opening.

8. In a tender, a fuel bin having a floor, a tender deck forward of said fuel bin forming a continuation of said fuel bin floor, said deck and floor having a continuous longitudinally elongated centrally disposed opening extending from the forward end of said deck to the rearward end of said floor, a stoker trough arranged to receive fuel from said bin, said trough having laterally projecting flanges overlapping said

floor adjacent the marginal sides of the opening therein, the opening in said deck being of a width such that the said trough flanges will overlap the deck upon insertion and removal of said trough through the forward end of the tender, the overlapped portion of said deck forming a guide support for said trough during its insertion and removal, and a platform supported on said deck forming a cover for the opening therein.

WILLIAM L. LENTZ.
EUGENE MARTIN.
